UNITED STATES PATENT OFFICE.

EDWARD THOMPSON MORRISS, OF SOUTH HAMPSTEAD, ENGLAND.

PERAMBULATOR, MAIL-CART, AND THE LIKE.

1,171,061.

Specification of Letters Patent. Patented Feb. 8, 1916.

Application filed March 21, 1912. Serial No. 685,175.

To all whom it may concern:

Be it known that I, EDWARD THOMPSON MORRISS, a subject of the King of Great Britain and Ireland, residing at 139^a Finchley road, South Hampstead, N. W., England, have invented certain new and useful Improvements Relating to Perambulators, Mail-Carts, and the like, of which the following is a specification.

10 This invention relates to perambulators, mailcarts and the like and has for its object to provide a light durable and inexpensive construction of frame therefor.

According to the invention the frame is 15 formed of a continuous length of tubing or of a length of tubing with a connected handle member, the frame being a quadrilateral or other closed figure when viewed in plan and being of a continuously curved shape 20 corresponding to the curved shape of the body.

The application of the invention to a perambulator is illustrated in the accompanying drawings in which:

25 Figure 1 is a side elevation of the perambulator and Fig. 2 is an end elevation corresponding thereto.

In carrying the invention into effect as 30 illustrated in the accompanying drawing, the frame *a* is constituted of steel or other suitable tubing bent in a continuous curvature to the required shape of the body and having its extremities connected by a handle-bar *b*, brazed or otherwise secured to the 35 adjacent ends of the pieces of tubing employed. The wheel axles *d* are carried by suitable brackets *f* mounted upon the tubing and brazed or otherwise secured in position.

The body *c* is carried upon the frame *a* by 40 means of a number of springs *e* attached at one end to the body and at the other end to hooks, loops or the like *g* secured to the

frame. It is preferred, however, to attach the springs to the frame by means of a stud passed through the eye of the spring, and 45 through a lug on the frame provided for that purpose. Bolts and nuts are preferably dispensed with.

If the frame *a* is formed of a number of 50 lengths of tubing coupled together by suitable sockets, these latter may be formed specially for the fixture thereto of the bearing members or carrying brackets of the wheel axles. The frame may if desired be formed of a single length of tubing having 55 the ends brazed together and bent or curved to the required shape.

It will be understood that the invention 60 may be applied also to toy perambulators and the like; and that the invention is not 50 limited to the means by which the frame is carried upon the wheels, nor to the manner in which the body is mounted upon the frame; nor yet to the shape of the tubular 65 frame.

What I claim as my invention and desire to secure by Letters Patent is:

A perambulator consisting of a frame of 70 tubing bent to a closed figure in plan and having a curved bow shape in elevation and 75 forming a light and resistant spring rising upwardly at each end, a body having a curvature corresponding to that of the frame and means for suspending the said body within the said frame at the upper ends 75 thereof consisting of spiral springs, substantially as described.

In testimony whereof I have hereunto signed my name to this specification in the presence of two subscribing witnesses.

EDWARD THOMPSON MORRISS.
